S. B. Dyer:

UNITED STATES PATENT OFFICE.

SIMPSON B. DYER, OF TULIA, TEXAS.

HARNESS-RACK.

1,083,203.

Specification of Letters Patent. Patented Dec. 30, 1913.

Application filed March 26, 1913. Serial No. 756,924.

To all whom it may concern:

Be it known that I, SIMPSON B. DYER, a citizen of the United States, residing at Tulia, in the county of Swisher and State of Texas, have invented new and useful Improvements in Harness-Racks, of which the following is a specification.

This invention is an improved harness rack especially adapted for holding and exhibiting a set of harness in a store or other place where harness is made or sold, the object of the invention being to provide an improved rack of this character which when in use serves to hold a set of harness so that all its parts are in correct relative position and may be readily inspected and when not in use may be readily disassembled and disposed compactly for shipment or storage, the invention consisting in the construction, combination and arrangement of devices hereinafter described and claimed.

In the accompanying drawings: Figure 1 is a side elevation of a harness rack constructed in accordance with my invention, showing the same set up and in use for exhibiting a set of harness. Fig. 2 is a detail sectional view of the same on the plane indicated by the line *a—a* of Fig. 1. Fig. 3 is a similar view on the plane indicated by the line *b—b* of Fig. 1. Fig. 4 is an elevation, showing the parts of my rack disassembled and arranged compactly for storage.

In accordance with my invention, I provide a standard 1 which is here shown as having screw holes 2 near its upper and lower ends to enable screws to be employed for fastening the standard to a wall, post or other suitable supporting object. An arm 3 is also provided which is arranged to be connected to the upper end of the standard and to extend horizontally therefrom. This arm is provided at its inner end, on its under side, with a downwardly extending shoulder 4 to bear against the standard and form a brace for the arm, and the arm is also provided on its under side, at its outer end and at a point a suitable distance therefrom with downwardly extending lugs 5—6 which have openings. A ring 7 extends through the opening in the lug 5 and a hook 8 has its eye engaged with the opening in the lug 6.

The standard is provided at its upper end, on opposite sides, with lugs 9 which extend therefrom and are adapted to bear on opposite sides of the inner end of the arm. These

lugs have openings. The inner end of the arm 3 also has an opening and a bolt 10 passes through the openings of the lugs and arm to detachably secure the arm to the standard, the shoulder 4 of the arm bearing 60 against the standard and, hence, acting as a brace or bracket to support the arm in a horizontal position. A winged nut 11 is screwed on the threaded end of the bolt and enables the bolt to be readily disconnected 65 from the lugs and arm and permits the detachment of the arm from the standard and the arrangement of the arm parallel with the standard when the rack is not in use and it is desired to dispose it compactly out of the 70 way. The standard is also provided at a point substantially midway between its upper and lower ends with a pair of lugs 12 between which the inner end of a hook arm 13 is secured by means of a bolt 14 which 75 has a winged nut 15. The said hook arm is provided at its inner end with a downwardly extending shoulder 16 to bear against the standard and support the hook arm in substantially horizontal position. This construction of devices enables the hook arm to be folded compactly against the standard out of the way when the rack is disassembled and is compactly disposed. A hook 17 is connected to and depends from the supporting shoulder 16 of the hook arm.

A chain 18 is provided with snap hooks or other suitable devices 19 at its ends. This chain, when the rack is in use is doubled and passed under the back bands of the harness 80 and the snap hooks being engaged with the ring 7, the chain serves to assist in suspending the harness from the arm.

A hook 8 is employed for hanging the bridles therefrom. The hook arm 13 is for 85 hanging the collars of the harness and the hook 17 is for hanging the lines. Hence, the rack with its various attaching devices serves to suspend the harness in something like the position of the harness when in use 100 on a horse and serves to fully display the harness in an attractive manner, and permit the ready inspection of all of its parts.

I claim:

1. A harness rack of the class described, 105 comprising a supporting standard, a horizontally arranged arm secured to the upper end of the standard, a hook arm also secured to the standard at a point below the horizontal arm, a bridle hanging hook at 110

tached to the inner end of the hook arm, and suspending devices attached to the horizontally arranged arm.

2. A harness rack of the class described, comprising a supporting standard, an arm having harness suspending devices attached thereto, means to detachably secure one end of the arm to the standard, means carried by the arm to bear against the standard and hold the arm in horizontal position when attached to the standard, a hook arm, means

to detachably connect the hook arm to the standard, means to support the hook arm in substantially horizontal position when extended from the standard, and a suspending hook carried by the hook arm. 15

In testimony whereof I affix my signature in presence of two witnesses.

SIMPSON B. DYER.
